TAPE HOLDER

Carl F. Prime, Chicago, Ill., assignor to Lion Manufacturing Corporation, Chicago, Ill., a corporation of Illinois

Application January 12, 1945, Serial No. 572,572

6 Claims. (Cl. 164—78)

1

The present invention relates in general to tapes and taping and has more particular reference to the provision of improved means for and method of subdividing or cutting up tapes to provide sections of limited, preferably uniform length, for use as tabs, the invention including means for supporting a plurality of such cut tabs in position for convenient selection and individual delivery at a station where used.

The tabs of the character herein contemplated find widespread use for marking and other purposes in trade and industry, and especially in the electrical industry where such tabs comprising paper or other fabric having a slow drying or non-drying adhesive coated upon one side of the tab, are used extensively for the purpose of marking conductors, coils, solenoids, and other electrical equipment, including transformer taps and coil sections. Tabs of the character mentioned are usually made by cutting up into tab sections, tapes of extended length, as supplied in rolls by the tape manufacturer, the tape as supplied being coated on one side, at least, with a suitable, usually slow or non-drying adhesive.

An important object of the present invention is to provide simple, yet exceedingly efficient means for cutting up tape to form tab sections; a further object being to provide for the simultaneous production of a relatively large number of tabs as a result of a single tab cutting stroke; a still further object being to provide support or holder means affording a mounting for the cut tab sections, such mounting being arranged to receive and support the tabs thereon as a result of the tab cutting stroke to hereby eliminate the necessity of separately mounting the cut tabs upon a suitable tab holder.

Another important object is to provide a tab holder on which a plurality of tabs may be mounted in side by side relationship in convenient position facilitating selection and removal of individual tabs therefrom for application as a part marker at an assembly station.

Another important object resides in the provision of means for cutting up, simultaneously, tapes of different indicating characteristics, usually of unlike color or carrying distinguishing markings, to form a plurality of contrasting tabs and at the same time mounting such contrasting tabs in side by side relationship on a common delivery support for selection and individual distribution therefrom, as in an assembly operation.

Another important object is to provide a tape cutting table comprising a plurality of removable

2

tab supports upon which a plurality of tape lengths may be applied and upon which such tape lengths may be cut up to provide tab sections in mounted position on the individual tab supports, the tabs on each individual support being of uniform length; a further object being to arrange the tab supports so that tabs formed on one support may be of length different from the length of tabs formed on other supports.

Another object is to form tab supports adapted for removable assembly in a main support frame to provide a cutting table, said supports being individually removable from the frame after the tab cutting operation and being mountable, as at an assembly station, to present the cut tabs, supported thereon, within convenient reach of a tab user at such assembly station.

The foregoing and numerous other important objects, advantages, and inherent functions of the invention will become apparent as the same is more fully understood from the following description, which, taken in conjunction with the accompanying drawings, discloses a preferred embodiment of the invention.

25 Referring to the drawings:

Fig. 1 is a perspective view of a tab holder mounted in position, as at an assembly station, to present cut tabs conveniently for ready removal and application, as in an assembly operation;

20 Fig. 2 is a top plan view of tape cutting table embodying a plurality of tab holders removably mounted in a support frame to form the cutting table in accordance with the present invention;

25 Fig. 3 is a sectional view taken substantially along the line 3—3 in Fig. 2;

Fig. 4 is an enlarged sectional view taken substantially along the line 4—4 in Fig. 3, on an enlarged scale; and

30 Fig. 5 is a sectional view taken substantially along the line 5—5 in Fig. 4.

To illustrate the invention, the drawings show tab cutting table means 11 comprising a support frame 13 and a plurality of tab supports 15 removably mounted in the frame. The tab supports 15 each comprise a tab supporting bar 17 which may conveniently comprise a strip of material having rectangular cross-sectional configuration and being made of any preferred material, such as fiber board, or a synthetic plastic, or other material, and the support frame 13 provides means whereby the bars 17 may be arranged in side by side, slightly spaced relationship to form a slat-like cutting table top.

35 The bars 17 are preferably provided with

mounting means for readily attaching the same on any convenient support at an assembly or other station at which the cut tabs are to be used. To this end, in the illustrated embodiment each bar 17 is provided with clips 19 comprising strips of sheet metal bent to form spaced apart clip arms 21, and a medial plate portion 23 adapted for attachment on the tab carrying bar 17 as by means of the nuts and bolts 25 as shown, although it will be apparent that any suitable fastening device may be employed for detachably mounting the tab support at an assembly station. As shown, the clips 19 afford means for mounting the tab support removably on a bar or rod 27, which may comprise part of an assembly bench.

The support frame 13 comprises a board 29 having dependent flanges 31 forming supports for mounting the board 29, as on a bench or table top on which the device may be used. The supports 31 serve to carry the board 29 at an elevation above such bench or table top. The board 29 in the illustrated embodiment is provided with a pair of slots 33, which extend in parallelism and adjacent the edges of the board in position to receive, therethrough, the clips 19 of the tab holders so that the bars 17 may be laid flat and in spaced parallel relationship on the cutting table. While any convenient means may be employed to maintain a desired spaced relationship of the bars 17, the spacing function in the illustrated embodiment is performed by the clips 19, which are slightly wider than the bars, and thus serve to maintain spacement between adjacent bars when the clips thereof are in engagement in the support frame. The top of the table, also, may be provided with grooves 35, along the edges of the slots 33, in order to accommodate the clip attaching bolts 25 so that the bars 17 may lie flat upon the top of the board 29.

After a plurality of tab supports 15 have been mounted in side by side relationship on the support frame 13, tape lengths 34 to be cut may be applied in side by side relationship, transversely across and upon the slat-like cutting table afforded by the bars 17. The tape lengths, of course, should be applied with their adhesive coated sides in engagement with and adhered to the upwardly facing surfaces of the bars 17. After as many tape lengths 34 as desired have been thus applied, said lengths may be cut along lines of intersection 36 to form individual tabs 38 in position adhering to the bars of individual tab supports merely by applying a suitable cutting knife 37 along the edges 40 of the bars 17 and across the top of the board 29. It will be noted that tabs of minimum length may thus be formed by applying the knife along corresponding edges 40 of each bar in the cutting table assembly. Longer tabs, however, may be formed either by providing wide bars 17, for some of the tab supports, or by omitting a cutting stroke between adjacent bars, as indicated at 39, to thereby provide long tabs mounted on a pair of adjacent bars. Still longer tabs may be formed, as shown at 41, by omitting the cutting stroke along the edges 40 of two or more adjacent bars to thereby provide tabs supported on three or more adjacent bars. In order to use such long tabs cut on two or more bars, the tabs may be easily detached from all but one of the support bars 17.

After formation of the cut tabs in position adhered on a tab support 15, such support and the cut tabs may be removed from the cutting table assembly as a unit and transported to an assembly or other work station, where the tabs

are to be used, and there mounted in position, on the support member 27, to allow a user of the tabs to select and strip off a desired tab for use in an assembly or other operation as needed. The member 27 may comprise any convenient rod, bar or other suitable mounting at the work bench or station where the cut tabs are used.

It will be obvious, of course, that tape lengths of any desired color or marked in a distinctive 10 fashion may be applied to the table so that a variety of distinguishing tabs may be cut and applied upon each of the tab supports 15 to the end that the user may have a wide selection of tabs instantly available for use at the assembly station.

15 It is thought that the invention and its numerous attendant advantages will be fully understood from the foregoing description, and it is obvious that numerous changes may be made in the form, construction and arrangement of the 20 several parts without departing from the spirit and scope of the invention, or sacrificing any of its attendant advantages, the form herein disclosed being a preferred embodiment for the purpose of illustrating the invention.

The invention is hereby claimed as follows:

1. A tabbing device comprising a plurality of tab bars, a frame for supporting said bars removably in spaced parallel relationship to provide a cutting table for the reception, transversely on said bars, of tape lengths, said bars providing edges along which said tape lengths may be severed for the formation of cut tabs on said bars, fastening means on said bars for securing the same, as on a support, in position to dispense tabs after removal of said bars from said cutting table, said frame comprising a board on which said bars may be laid for support and having cut out portions for the reception of said 40 fastening means.

2. The method of cutting adhesive coated tape lengths to produce tabs which consists in arranging a plurality of tape lengths in parallel relationship and transversely of a tape supporting bar, and adhering said tape lengths to the bar, and then intersecting said tape lengths along an edge of said bar to produce cut tabs adhering to the bar in side by side relationship, and then removing said bar with the cut tabs thereon and placing the same in position that the tabs may be selected and stripped off of the bar for tabbing purposes.

3. The method of cutting adhesive coated tape lengths to produce tabs which consists in arranging a plurality of tape lengths in parallel relationship and transversely of a plurality of parallel spaced apart tab supporting bars, and adhering said tape lengths to said bars, then intersecting said tape lengths along corresponding edges of said bars to provide cut tabs adhering, in side by side relationship, on each of said bars, then removing and selectively placing said bars with the tabs thereon in position so that the cut tabs may be selected and stripped off from the bar for tabbing purposes.

4. A tabbing device comprising a support, a plurality of tab bars adapted to be mounted on said support to form a supporting surface for receiving strips of tape, and clip means affixed to said bars, said clip means being adapted to position said bars on said support and interengaged to hold said bars in spaced relationship on said support, said clips being also adapted to secure said bar to a second support.

5. A tabbing device comprising a support hav-

ng elongated slots therein, a plurality of tab bars adapted to be mounted on said support to form a supporting surface for receiving strips of tape, and a pair of clips affixed to each of said bars, said clips being adapted to be inserted into said slots to position said bars on said support and interengaged to hold said bars in spaced relationship, said clips being also adapted to secure said bar to a second support.

6. A tabbing device comprising a support, a plurality of tab bars adapted to be mounted on said support, said tab bars having a flat surface which forms a uniform plane supporting surface for receiving strips of tape when mounted on said support, and clip means affixed to said bars, said 10 clip means being adapted to position said bars on said support and interengaged to hold said bars in spaced relationship on said support, said clips

being also adapted to secure said bar to a second support.
